KNIFE HEAD FOR HARVESTERS

Filed March 20, 1922

Inventor:
Robert C. Livesay
By W.C. Indinton
Attorney

W.H. 1255,
E. Wilderson

UNITED STATES PATENT OFFICE.

ROBERT C. LIVESAY, OF MOLINE, ILLINOIS, ASSIGNOR TO DEERE & COMPANY, OF MOLINE, ILLINOIS, A CORPORATION OF ILLINOIS.

KNIFE HEAD FOR HARVESTERS.

Application filed March 20, 1922. Serial No. 545,110.

To all whom it may concern:

Be it known that I, ROBERT C. LIVESAY, a citizen of the United States, residing at Moline, in the county of Rock Island and State 5 of Illinois, have invented certain new and useful Improvements in Knife Heads for Harvesters, of which the following is a specification, reference being had therein to the accompanying drawing.

10 My invention relates to knife heads for harvesting machines in which a reciprocating knife is employed to cut the standing grain, and the object of my invention is the production of a simple and efficient device, 15 economically constructed of steel and provided with a novel type of ball bearing for the pitman, and a wear plate which can be readily removed and substituted with another or repaired.

20 Referring to the drawings in which similar numerals indicate identical parts—

Figure 1 is a plan view of a complete knife head embodying my improvements. Figure 2 is a rear elevation of Figure 1. Figure 3 25 is a section on the line 3—3 of Figure 1. Figure 4 is a transverse vertical section of a part of the ball bearing. Figure 5 represents the wear or cushion plate, and Figure 6 is a view of the casting forming part of the 30 ball bearing.

The part 1 of the knife head includes a shank 2 provided with perforations for rivets by which it is fastened to the knife bar 3, shown in dotted lines. At the pitman 35 end of the part 1 an extension 4 is bent vertically at substantially a right angle, and formed thereon is a substantially hemispherical cup 5 having a central outwardly beveled aperture 6; this cup 5 forms one half 40 of the bearing to which the pitman is to be connected. A substantially hemispherical part 7 of a member 8, similar in diameter to the cup 5, forms the second part of the bearing and is secured to the first half by a substantially hemispherical part 9, of the member 45 8, which fits snugly within the cup 5 and is provided with a tubular stud 10 projecting into the aperture 6. By suitable pressure the stud 10 is expanded, within the 50 opening 6, into rigid contact with the bevelled surface of the opening 6.

As stated the member 8 is formed of two substantially hemispherical parts 7 and 9; these parts are preferably integral, the part

7 having the same outside diameter as the 55 cup 5, and the part 9 having the same diameter as the inside of the cup 5. The difference in the diameters of the two parts results in an annular surface or shoulder 11 which is drawn tightly against the edge of 60 the cup 5, by the expansion of the tubular stud 10, so that a compact spherical bearing is presented to which the pitman is to be attached.

A wear plate 12 is riveted to the pitman 65 end of the part 1 and to the knife bar 3 of the knife head and can be readily detached therefrom when continuous operation results in such wear as to require repair or the substitution of another. 70

What I claim is—

1. A knife head formed of sheet metal and including a vertical web having a substantially hemispherical cup shaped projection on one side thereof, and a member secured within said cup and having a projecting substantially hemispherical part co-operating with said cup shaped projection to form a substantially spherical bearing. 75

2. A knife head formed of sheet metal 80 and including a vertical web having a substantially hemispherical cup shaped projection on one side thereof, a member having a substantially hemispherical part secured within said cup, and having a substantially 85 hemispherical part projecting from the cup beyond the opposite side of said web and co-operating with said cup to form a substantially spherical bearing.

3. A knife head formed of sheet metal 90 and including a vertical web having a substantially hemispherical cup shaped projection on one side thereof having a central aperture, a member having a substantially hemispherical part adapted to be positioned 95 within the cup and having means expansive in said aperture to hold said member rigidly with the cup, and a substantially hemispherical part of said member projecting beyond the web and co-operating with said cup to 100 form a substantially spherical bearing.

4. A knife head formed of sheet metal and including a vertical web having a substantially hemispherical cup shaped projection on one side thereof with a central opening, 105 a member having a substantially hemispherical part adapted to be positioned within the cup, a stud on said part extending into

said aperture and expansible therein to hold said member rigidly with the cup, and a substantially hemispherical part of said member projecting beyond the web and co-operating with said cup to form a substantially spherical bearing.

5. A knife head formed of sheet metal and including a vertical web having a substantially hemispherical cup shaped projection on one side thereof, an outwardly beveled aperture in said cup, a member having a substantially hemispherical part adapted to be positioned within the cup, a stud on said part extending into said aperture and expansible therein to contact with the beveled surface of said aperture to hold said member and cup rigidly together, and a substantially hemispherical part of said member projecting beyond the web and co-oper-

ating with said cup to form a substantially spherical bearing.

6. A knife head formed of sheet metal and including a vertical web having a substantially hemispherical cup shaped projection on one side thereof with a central aperture, a member composed of two opposed substantially hemispherical parts, one of said parts having the same diameter as the inside of the cup and adapted to be positioned therein, the second part having the same diameter as the outside of the cup and co-operating with said cup to form a substantially spherical bearing, and a stud on the substantially hemispherical part in the cup extending into said aperture and expansible therein to hold said member and cup rigidly together.

ROBERT C. LIVESAY.
